Primary Examiner — Darlington Ly*Assistant Examiner* — Katherine A Holbrow(74) *Attorney, Agent, or Firm* — Caitlyn Ross(57) **CLAIM**

The ornamental design for a display screen with graphical user interface, as shown and described.

DESCRIPTION

FIG. 1 is a front view of a first embodiment of a display screen with graphical user interface, showing our new design;

FIG. 2 is another front view of the first embodiment, shown in the context of different broken lines;

FIG. 3 is a second embodiment thereof; and,

FIG. 4 is a third embodiment thereof.

The broken lines showing a device, display screen and portions of the graphical user interface form no part of the claimed design.
